DESCRIPTION

FIG. 1 is a top perspective view of the 3D glasses;

FIG. 2 is a front elevation view of the 3D glasses of FIG. 1;

FIG. 3 is rear elevation view of the 3D glasses of FIG. 1;

FIG. 4 is a left side elevation view of the 3D glasses of FIG. 1;

FIG. 5 is a top plan elevation view of the 3D glasses of FIG. 1;

FIG. 6 is a bottom plan elevation view of the 3D glasses of FIG. 1;

FIG. 7 is a top perspective view of the 3D glasses;

FIG. 8 is a front elevation view of the 3D glasses of FIG. 7;

FIG. 9 is rear elevation view of the 3D glasses of FIG. 7;

FIG. 10 is a left side elevation view of the 3D glasses of FIG. 7;

FIG. 11 is a top plan elevation view of the 3D glasses of FIG. 7;

FIG. 12 is a bottom plan elevation view of the 3D glasses of FIG. 7;

FIG. 13 is a top perspective view of the 3D glasses;

FIG. 14 is a front elevation view of the 3D glasses of FIG. 13;

FIG. 15 is rear elevation view of the 3D glasses of FIG. 13;

FIG. 16 is a left side elevation of the 3D glasses of FIG. 13;

FIG. 17 is a top plan elevation view of the 3D glasses of FIG. 13;

FIG. 18 is a bottom plan elevation view of the 3D glasses of FIG. 13;

FIG. 19 is a top perspective view of the 3D glasses;

FIG. 20 is a front elevation view of the 3D glasses of FIG. 19;

FIG. 21 is rear elevation view of the 3D glasses of FIG. 19;

FIG. 22 is a left side elevation view of the 3D glasses of FIG. 19;

FIG. 23 is a top plan elevation view of the 3D glasses of FIG. 19;

FIG. 24 is a bottom plan elevation view of the 3D glasses of FIG. 19;

FIG. 25 is a top perspective view of the 3D glasses;

FIG. 26 is a front elevation view of the 3D glasses of FIG. 25;

FIG. 27 is rear elevation view of the 3D glasses of FIG. 25;

FIG. 28 is a left side elevation view of the 3D glasses of FIG. 25;

FIG. 29 is a top plan elevation view of the 3D glasses of FIG. 25; and,
FIG. 30 is a bottom plan elevation view of the 3D glasses of FIG. 25.
